COP BAGGER

Joseph Elmer Heckel, Oak Park, Ill., assignor to Olson Rug Company, Chicago, Ill., a corporation of Illinois
Application September 8, 1955, Serial No. 533,181
7 Claims. (Cl. 53—124)

This invention relates to what I term a "cop bagger" for use in textile plants such as rug and carpet factories. Its purpose is to facilitate the assembly and bagging of cops which, as is understood in the industry, are coils of thread or yarn wound on spindles. They are formed on winding machines and, upon delivery therefrom, they are customarily bagged for convenient handling and transporting to other machines employed in the process of manufacture of rugs and carpets or other textile products.

The principal object of the invention is to provide an efficient and easily operated device or machine for this purpose.

A further object is to provide in such a machine means whereby the cops may be compressed into a tight bundle and enclosed within a wrapper or bag which may be readily closed over the bundle and fastened before removal of the bundle from the machine.

Another object of the invention is to provide an apparatus of this character which can be loaded and operated conveniently by a single operator. To this end the apparatus employs an actuating lever arm of special construction which is easy to operate and may be actuated, if desired, by a foot pedal, leaving the operator's hands and arms free for handling the cops and manipulating the edges of the wrapper to close the same and fasten them together by means of snap-on fasteners or other appropriate fastening devices.

A still further object of the invention is to provide an apparatus for the purpose stated which is so constructed that the compression of the cops is accomplished by a wedging mechanism through which powerful leverage may be applied without undue exertion on the part of the operator.

Other objects and advantages of the invention will be apparent from the following description, taken in connection with the accompanying drawings, in which:

Fig. 1 is a front elevational view of the machine with the cop compressor in open position;

Fig. 2 is a side elevational view thereof;

Fig. 3 is a top plan view;

Fig. 4 is a fragmentary elevational view showing the cop compressor in closed position;

Fig. 5 is a transverse sectional view taken substantially on the section line 5—5 in Fig. 1;

Fig. 6 is a sectional detail taken substantially on the section line 6—6 in Fig. 1;

Fig. 7 is a vertical sectional view taken substantially on the section line 7—7 in Fig. 2, showing the clevis by which a pull rod for operating the cop compressor is connected with the actuating lever arm;

Fig. 8 is a vertical sectional view of the same mechanism taken at right angles to Fig. 7 and substantially on the section line 8—8 in the latter figure;

Fig. 9 is a perspective view of a closed cop bag or package with part of the wrapper broken away for convenience in illustration.

In the preferred embodiment of the invention illustrated by way of example in said drawings, the apparatus is shown as mounted upon a base 11 to which a stand 12 comprising two uprights 13 and a steel pipe 13' arises, said uprights being secured to the base by angular foot pieces 14 and hexagon head cap screws 15.

A tubular sheet metal frame 16 is attached to the uprights 13 by means of cap screws 17 and has a wedging

2

inner portion 18 of generally concave formation, which is best shown in Figs. 1, 4 and 5.

Disposed within the concavity 18 is the above-mentioned cop compressor, which is generally indicated by the numeral 19. This compressor comprises two sheet metal wings or walls 21 which are hinged together at their lower central portions by a hinge pin 22. A pull rod 23 is connected to, and extends downwardly from, said hinge pin through the pipe 13'. At its lower end said rod is pivotally connected with an actuating lever arm which is generally indicated at 24 in Fig. 2. The attachment is effected by means of a clevis 25 which is best shown in Figs. 7 and 8. The lower end of the rod 23 is threaded and is screwed into a socket portion 26 of said clevis. The lower part 27 of the clevis is bifurcated and straddles an upper lever arm 28 forming a part of the lever arm structure 24, being connected to said arm 28 by a hinge pin 29.

Said arm 28 is hinged at 31 to a bracket 32 arising from the base 11 and attached thereto by an angle member 32', and a second lever arm, numbered 33, is disposed immediately below and parallel to said arm 28, said arm 33 being pivoted to the bracket 32 at 34.

At their forward ends said arms 28 and 33 are pivotally secured, at 35 and 36, respectively, to ears 37 on an angle foot-piece or pedal 38.

A tail piece 39 on the arm 28 projects rearwardly and upwardly beyond the upright 32 and is connected with the end of a closed extension spring 41 which in turn is connected at its lower end with a cap screw 42 fixedly secured to the base structure.

Pressure arms 43 are connected at their inner ends by pivot pins 44 to upper end portions 45, of channel formation, of the frame 16; and at their outer ends said arms 35 are pivotally connected by rods 46, curved straps 47 and wing nuts 48 to the outer portions of the cop compressor members 21.

A canvas strip 49 may be placed inside the sheet metal members 21 of the cop compressor 19, guide pins 51 being provided to hold said strip close to the interior of said members. The ends of the strip may be extended around the outer edges of said members 21 and clamped by means of toggle-action clamps 52 against rolled portions of the curved attachment straps 47 surrounding the rods 46. Said clamps are provided with hand-pieces 53 for manual operation thereof to grip or release the ends of the canvas strip (which ultimately forms the bag or wrapper), and inwardly from the ends of the strip snap-on fasteners 54, 54' are provided for closing the ends together before the package is removed from the machine.

Vertically disposed disks 55 are provided on the members 21 at the rear side of the machine to provide a backing against which the cops, which are identified by the numeral 56, may abut when being placed in the bag-forming strip 49 that is disposed within the compressor.

In use, one or more of the machines of my invention may be placed near the discharge end of each cop winding machine in the factory. An attendant, having placed a canvas strip (formed as above described) in the compressor element of the machine, with the latter open and the ends of the strip held as shown in Fig. 1 of the drawings, places the cops in the compressor. The proper positioning of them therein is facilitated by the backing disks 55, against which one end of the cops may be pressed.

At one or more stages as the compressor fills up the cops may be preliminarily compressed by manipulation of the pressure arms 43 by means of the hand levers 53 and the compressor wall elements 21 will stay in their adjusted position. When the package has been loaded to capacity, the attendant steps on the foot pedal 38 and

presses it down against the force of the spring 41. As the compressor wings or walls 21 are moved downwardly they will be closed by wedging action against the inner walls of the concavity 18 of the frame member 16 and brought to the closed position substantially as shown in Fig. 4.

The construction of the lever arm structure 24, with the two separately hinged levers 28 and 33 pivotally connected with the foot pedal, facilitates the operation of the mechanism and permits the foot pedal to remain in horizontal position as it is moved up or down.

The final increment of the closing movement of the wings or jaws 21 is effected by the pressure arms 43, through manipulation of the levers 53. With the parts in the position shown in Fig. 4, the ends of the canvas strip may be released, by slight movement backward on their pivots, of the arms 53, thus raising rollers 57, which form a part of the toggle-action clamps, from the position in which they hold the ends of the strip in pressure contact with the pressure arm attachment elements 46, 47. The operator may then manually press the female and male snap fastening elements 54 and 54' together to close the bag, thus making a compact and easily handled package as shown in Fig. 9.

The package may be withdrawn from the open end of the compressor after the pressure has been relieved sufficiently for this purpose.

It will be evident that after release of both the foot pedal 38 and the pressure arms 43 the spring 41 will return the compressor elements to their upper and open position shown in Fig. 1.

While I have shown my invention in but one form, it will be obvious to those skilled in the art that it is not so limited, but that various changes and modifications may be made in the particular embodiment thereof without departing from the spirit and scope of the invention.

I claim:

1. A cop bagger comprising: a frame; a cop compressor mounted thereon and including two hingedly-connected arcuate jaw members arranged to receive as a liner a bag strip into which the cops may be placed; actuating mechanism for moving said compressor downwardly; and fixed wedging mechanism whereby said jaw members and the bag strip positioned therein are closed upon the cops by such downward movement of the compressor, thereby compressing the cops into a tight bundle and disposing the ends of the strip in position to be readily fastened together.

2. A cop bagger comprising: a frame having a wedging recess therein; a cop compressor mounted on said frame and including two hingedly-connected arcuate jaw members arranged to receive as a liner a bag strip into which the cops may be placed; and actuating mechanism for moving said compressor downwardly into said recess, whereby said jaw members and the bag strip positioned therein are closed upon the cops by such downward movement of the compressor, thereby compressing the cops into a tight bundle and disposing the ends of said strip, which may have interconnectable fastening devices thereon, in position to be readily fastened together.

3. A cop bagger comprising: a frame; a cop compressor mounted thereon and including two hingedly-connected arcuate jaw members arranged to receive as a liner a bag strip into which the cops may be placed; toggle-action devices for releasably clamping the ends of the positioned strip and holding the same during the loading of the compressor; actuating mechanism for moving said compressor bodily; and wedging mechanism whereby said jaw members and the bag strip positioned therein are closed upon the cops by such bodily movement of the compressor, thereby compressing the cops into a tight bundle and disposing said ends of the strip, which may have interconnectable fastening devices thereon, in position to be readily fastened together.

4. A cop bagger comprising: a frame; a cop compressor mounted thereon and including two hingedly-connected arcuate jaw members arranged to receive as a liner a bag strip into which the cops may be placed; pressure arms pivotally connected to said frame and to said jaw members; toggle-action devices mounted on said pressure arms for releasably clamping the ends of the positioned strip and holding the same during the loading of the compressor; actuating mechanism for moving said compressor bodily; and wedging mechanism whereby said jaw members and the bag strip positioned therein are closed upon the cops by such bodily movement of the compressor, thereby compressing the cops into a tight bundle and disposing said ends of the strip, which may have interconnectable fastening devices thereon, in position to be readily fastened together.

5. A cop bagger comprising: a frame; a cop compressor mounted thereon and including two hingedly-connected arcuate jaw members arranged to receive as a liner a bag strip into which the cops may be placed; a lever arm structure, including a pull-rod connected to said compressor, an actuating lever structure to which said rod is pivotally connected, said structure including a frame upright, two lever arms separately pivoted to said upright, at least one of said arms being spring-loaded, and a foot pedal so connected to the free ends of said arms that said pedal will remain in horizontal position as it is moved up and down, for moving said compressor bodily; and fixed wedging mechanism whereby said jaw members and the bag strip positioned therein are closed upon the cops by such bodily movement of the compressor, thereby compressing the cops into a tight bundle and disposing said ends of the strip, which may have interconnectable fastening devices thereon, in position to be readily fastened together.

6. A cop bagger comprising: a frame; a cop compressor mounted thereon and including two hingedly-connected arcuate jaw members arranged to receive a bag strip into which the cops may be placed; actuating mechanism, including a pull rod connected to said compressor and a spring-loaded, foot-operated lever arm structure for moving said compressor downwardly; and fixed wedging mechanism whereby said jaw members and the bag strip positioned therein are closed upon the cops by such downward movement of the compressor, thereby compressing the cops into a tight bundle and disposing said ends of the strip, which may have interconnectable fastening devices thereon, in position to be readily fastened together.

7. A cop bagger comprising: a frame; a cop compressor mounted thereon and including two hingedly-connected arcuate jaw members arranged to receive as a liner a bag strip into which the cops may be placed; toggle-action devices for releasably clamping the ends of the positioned strip and holding the same during the loading of the compressor; actuating mechanism for moving said compressor bodily; and mechanism whereby said jaw members and the bag strip positioned therein are closed upon the cops by such bodily movement of the compressor, thereby compressing the cops into a tight bundle and disposing said ends of the strip, which may have interconnectable fastening devices thereon, in position to be readily fastened together.
